DISH STAND OR SIMILAR ARTICLE

Lee Goldman, New York, N. Y., assignor to Corning Glass Works, Corning, N. Y., a corporation of New York

Application May 10, 1951, Serial No. 15,128

Term of patent 7 years

(Cl. D44—29)

To all whom it may concern:

Be it known that I, Lee Goldman, a citizen of the United States of America, residing at New York, in the county of New York and State of New York, have invented a new, original, and ornamental Design for a Dish Stand or Similar Article, of which the following is a specification, reference being had to the accompanying drawing, forming a part thereof.

Fig. 1 is a side elevational view of a dish stand showing my new design.

Fig. 2 is a view similar to Fig. 1 but with the dish stand turned 90°.

Fig. 3 is a fragmentary top plan view of the dish stand of Fig. 1 taken in the direction indicated by the arrows 3—3.

The broken line showing of a dish in Figs. 1 and 2 is made solely for the purpose of illustrating a manner of using the dish stand.

In each of Figs. 1 and 2 only a half of the dish stand is shown, the obscured rear half in each case being an exact duplicate of the front half as shown and a continuation thereof.

I claim:

The ornamental design for a dish stand or similar article, substantially as shown and described.

LEE GOLDMAN.
